UNITED STATES PATENT OFFICE.

WILLIAM H. BARBOUR, OF NEW YORK, N. Y., ASSIGNOR TO E. G. WEBSTER
AND F. H. WEBSTER, OF SAME PLACE.

DESIGN FOR A MATCH-BOX OR SIMILAR ARTICLE.

SPECIFICATION forming part of Design No. 31,401, dated August 15, 1899.

Application filed August 27, 1897. Serial No. 649,787. Term of patent 3½ years.

To all whom it may concern:

Be it known that I, WILLIAM H. BARBOUR, a citizen of the United States, and a resident of New York, Brooklyn borough, in the county of Kings and State of New York, have invented and produced a new and original Design for Match-Boxes or Similar Articles, of which the following is a specification, reference being had to the accompanying drawing, forming part thereof, in which an elevation of a match-box bearing the design is shown.

The leading or material feature of the design consists in an aggregation of curvilinear members or figures arranged in sets or groups, whereby each individual member produces its proper optical effect, and also the several members comprising each group constitute what may be called a "subfigure" or "member" of the general design—that is to say, commencing at the center, *a* represents the figure of a conventionalized shamrock, and *b b* represent a series of curvilinear or scroll-like figures, arranged in pairs, which are grouped about the central or shamrock figure, which, together with cloverleaf figures *c*, constitute another member or feature of the design out-

side of the central or shamrock figure. Outside of these latter figures or members are still other figures *d d*, which have inwardly-extending scroll-like members *e e* and outwardly-extending scroll-like members *ff*, &c. These figures are so arranged as to constitute an exterior assemblage or arrangement of members forming the outer portions of the design. The entire design is filled in with scrollwork and blossom-like members to complete the background.

This design as a whole is repeated any desired number of times, depending upon the size of the surface to be decorated.

I employ this design in the manufacture of enameled metallic vessels, such as match-boxes and the like.

Having described my invention, what I claim as new, and desire to secure by Letters Patent, is—

The design for a match-box or similar article herein shown and described.

WILLIAM H. BARBOUR.
